UNITED STATES PATENT OFFICE

146,612

DESIGN FOR A CHILD'S DESK

Dorothy Mellick, North Plainfield, N. J.

Application March 12, 1946, Serial No. 127,388

Term of patent 14 years

(Cl. D34—15)

To all whom it may concern:

Be it known that I, Dorothy Mellick, a citizen of the United States, residing at 138 Norwood Avenue, North Plainfield, New Jersey, have invented a new, original, and ornamental Design for a Child's Desk, of which the following is a specification, reference being had to the accompanying drawing, forming part thereof.

In the drawing:

The figure is a three-quarter perspective view taken from above the child's desk showing my new design.

The side of the desk opposing the side which is shown is identical in design to the side shown. The rear of the desk is conventional and the essential features of the design reside in the portions shown in full lines on the drawing.

I claim:

The ornamental design for a child's desk, substantially as shown and described.

DOROTHY MELLICK.
